UNITED STATES PATENT OFFICE

WILLIAM B. HOLMES, OF HAMMONTON, NEW JERSEY

LADDER-JACK-SUPPORTING DEVICE

Application filed March 2, 1929. Serial No. 343,966.

This invention relates to an improved supporting device in the form of an attachment for ladder and constructed to be used in conjunction with devices such as are commonly referred to in mechanical trade as jacks, brackets, and the like.

At the present time it is customary to provide auxiliary platforms and attaching means therefor which structure is generally referred to as a jack. The attaching means is so made as to be connected with the side rails, or the rungs of the ladder, and the device is capable of detachable placement on the ladder near the top in order that it will form a convenient support for the workman in painting, shingling, roofing, work and the like.

The purpose of the present invention is to provide a more dependable means for enabling the jack to be connected thereto, the means being such as to permit it to be applied to the ladder without requiring alterations in the existing details.

Briefly stated, the improved supporting device comprises a pair of longitudinal side bars disposed in spaced parallelism and connected together by vertically spaced transversely extending cross bars functioning as supplemental rungs, and side bars formed with hooks to engage over the rungs on the ladder to hold the device securely in place.

In carrying out the invention I have evolved and produced an attachment which is exceptionally inexpensive, practical in use, susceptible of easy application and removal, capable of being folded into a compact package for convenient handling and transportation, and otherwise well adapted to fulfill the requirements of an invention of this class in a satisfactory manner.

In the drawings:

Figure 1 is a front elevational view showing the device applied to the ladder.

Figure 2 is a vertical section on an enlarged scale showing the manner in which the jack (shown in dotted lines) is associated with the supporting device.

Figure 3 is a view of the lower end of one of the side bars of the device showing the pivoted retaining latch.

Figure 4 is an elevational view showing the device folded.

Figure 5 is a perspective view of the device ready for application to the ladder.

Referring first to Figure 5 it will be observed that the device, which as before stated is in the form of an attachment, is generally designated by the reference character 6. It is of general frame like configuration and is made of comparatively sturdy metal parts. It embodies spaced parallel duplicate side bars 7 having their upper ends bent upon themselves to provide hanger hooks 8. Similar hooks 9 are formed on the lower ends of these bars. The intermediate portions of the side bars are also bent as at 10 to provide U-shaped rung embracing portions. Thus each side bar is formed with a series of four distinct fasteners for separable engagement with the supplemental rungs of the ladder. In addition, the device comprises cross bars 11 fastened to the side bars by bolt and nut fastening devices 12. This arrangement allows the structure to be expanded into a frame like form seen in Figure 5 or folded into the compact form seen in Figure 4. It is yet to be mentioned that one or more latches 13 are provided. I have shown a single latch in Figure 4 and it cooperates with one of the bottom hooks 9.

In practice the device is attached to the ladder 14 as shown in Figures 1 and 2. In this figure the rungs are designated by the reference character 15 and the side rails by the reference character 16. The device when placed in position occupies the approximate place seen better in Figure 1. Here the supplemental cross bars are disposed between the main rungs 15. Moreover the side bars 7 are disposed against the inner sides of the rails 16 of the ladder, thereby equally distributing the strain and insuring rigidity in action.

As shown in Figure 2 the reference character 17 designates a conventional jack. This comprises horizontal arms 18 having attaching hooks 19 to engage over a supplemental bar 11. A platform board 20 is disposed across these arms. In addition there are depending diagonal braces 21 hav-

ing hooks 22 at their lower ends to engage over the lowermost bar. There are three of these cross bars 11, thereby permitting the device 17 to be vertically adjusted within a limited ring. However, the entire device 5 may be bodily adjusted and hooked on such rungs as are desired.

A careful consideration of the description in conjunction with the drawings will enable 10 the reader to obtain a clear understanding of the construction, operation and features and advantages of the invention. Therefore, a more lengthy description is regarded unnecessary.

15 Minor changes in shape, size, and rearrangement of details coming within the field of invention claimed may be resorted to in actual practice if desired.

Having thus described the invention, what 20 I claim as new and desire to secure by Letters Patent is:—

1. As a new product of manufacture, an attaching and supporting device for a workman's jack of the class described comprising 25 a pair of duplicate side bars provided with attaching hooks, and a plurality of transversely disposed longitudinally spaced cross bars connected with the side bars and functioning as supplemental rungs, said cross 30 bars being pivotally connected to the side bars, whereby to permit the structure to be folded into a compact package.

2. As a new product of manufacture, a workman's jack supporting and attaching 35 device comprising a frame like structure embodying a pair of spaced parallel longitudinal side bars adapted for disposition between and in contact with the inner surfaces of the side rails of conventional ladder, said 40 side bars having means for connecting with the rungs of a ladder, and a plurality of longitudinally spaced transversely extending cross bars connected with the intermediate portions of said side bars.

45 3. As a new product of manufacture, a ladder attachment for use in association with a workman's jack of the class described comprising a frame like structure embodying a pair of spaced side bars formed with intermediate 50 U-shaped rung embracing portions and provided at their opposite ends with rung engaging hooks, and cross bars connected with the side bars.

55 4. As a new product of manufacture, a ladder attachment for use in association with a workman's jack of the class described comprising a frame like structure embodying a pair of spaced side bars formed with intermediate 60 U-shaped rung embracing portions and provided at their opposite ends with rung engaging hooks, and cross bars connected with the side bars, said cross bars being pivotally bolted to said side bars, whereby to permit the structure to be folded 65 into a compact package.

5. A ladder attachment of the class described for use in association with a workman's jack or bracket comprising a foldable frame like device including a pair of longitudinal spaced parallel side bars formed at their upper ends with rung engaging hooks and at their lower ends with additional rung engaging hooks, a pivoted retaining latch operable with one of the hooks on the lower end of one of said side bars, the intermediate portions of said side bars being bent to form additional rung embracing portions, and a plurality of longitudinally disposed transversely extending cross bars pivotally bolted to the side bars.

In testimony whereof I affix my signature.

WILLIAM B. HOLMES.
